(57) **CLAIM**

The ornamental design for an apparatus for handling fluent material, as shown and described.

DESCRIPTION

FIG. 1 is a perspective view of an apparatus for handling fluent material, showing my new design;
FIG. 2 is a left side view thereof;
FIG. 3 is a front elevational view thereof;
FIG. 4 is a rear elevational view thereof; and,
FIG. 5 is a top plan view thereof.

The broken lines in FIG. 5 indicate portions of the apparatus which are not part of the claimed design. The right side view, not shown, also forms no part of the claimed design.
